UNITED STATES PATENT OFFICE.

FLAVIEN BOMBARDIER, OF VALCOURT, QUEBEC, CANADA.

RAILWAY-RAIL JOINT.

No. 832,715.

Specification of Letters Patent.

Patented Oct. 2, 1906.

Application filed July 2, 1906. Serial No. 324,853.

To all whom it may concern:

Be it known that I, FLAVIEN BOMBARDIER, a subject of the King of Great Britain, residing at Valcourt, county of Shefford, in the Province of Quebec, Canada, have invented certain new and useful Improvements in Railway-Rail Joints; and I do hereby declare that the following is a full, clear, and exact description of the invention, such as will enable others skilled in the art to which it appertains to make and use the same.

My invention relates to railway-rail joints.

The object of my invention is to provide a continuous joint which will not give under the passage of a train and which will permit expansion and contraction longitudinally of the rail.

A further object is to provide a joint in which both of the abutting ends of the rail may be held in position by a single spike without the use of bolts; and my invention consists of the construction, combination, and arrangement of parts, as herein illustrated, described, and claimed.

In the accompanying drawings, forming part of this application, I have illustrated one form of embodiment of my invention, in which drawings similar reference characters designate corresponding parts, and in which—

Figure 1 is a perspective, and Fig. 2 is a side elevation, of the abutting ends of rails, shown separated, but in their relative operative position.

Referring to the drawings, 1 designates the base, 2 the web, and 3 the tread, of one rail, which has a thickened shoulder 4 adjacent the end of the web 2. The shoulder 4 is cut away to leave the vertical inwardly-converging faces 5, which faces are at an acute angle to the longitudinal central line of the rail. The web 2 and tread 3 are extended to form the projecting tongue 6 and cut away to provide the rectangular lugs 7 on the opposite sides thereof. The base 1 is cut away to form the projecting lip 8. The other rail, forming a part of the joint, is provided with a base 9, a web 10, and a tread 11, the web 10 of which is provided with a thickened shoulder

12. The thickened shoulder 12 terminates in the vertical inwardly-converging faces 13, adapted to bear against the corresponding faces 5 of the other rail. The second rail is provided with a vertical slot 14 through its thickened portion 12, the wall of which slot 14 is provided with rectangular recesses 15 of

greater dimensions in one direction than the lugs 7, which are disposed in said slots when the parts are locked in operative position. The thickened shoulder 12 of the second rail is provided with a cut-out portion 16, adapted to rest on the upper face of the base 1, and is further provided with a cut-out portion 17, adapted to lie on the upper face of the lip 8 of the other rail, and is further provided with a shoulder 18, adapted to abut against the end of the projecting lip 8.

As best shown in Fig. 1, a single spike 19 is adapted to be driven into the tie 20 and to lock the base 9 of one rail on the base 1 of the other rail, so that the abutting ends may be held against vertical movement by a single spike. The construction of the faces 5 and 13 and of the recesses 15 and lugs 7 effectively prevents lateral movement of the rails. The recesses 15 being of greater dimension along the longitudinal line of the rails than the lugs 7, longitudinal expansion of the joint is permitted.

Having thus fully described my invention, what I claim as new, and desire to secure by Letters Patent, is—

1. A rail-joint comprising a rail having a thickened shoulder with its end cut away to leave vertical inwardly-converging faces and to leave a projecting tongue having a plurality of locking-lugs on its opposite sides, and a second rail having a thickened shoulder with a central slot provided with recesses in the walls thereof, to receive said locking-lugs, and said second rail having inwardly-converging faces adapted to bear on the inwardly-converging faces of the first rail.

2. A rail-joint comprising a rail having a thickened shoulder with its end cut away to leave vertical inwardly-converging faces and to leave a projecting tongue having a plurality of rectangular locking-lugs on its opposite sides, and a second rail having a thickened shoulder with a central slot provided with rectangular recesses in the walls thereof to receive said locking-lugs, and said second rail having inwardly-converging faces adapted to bear on the inwardly-converging faces of the first rail.

3. A rail-joint comprising a rail having a thickened shoulder with its end cut away to leave vertical inwardly-converging faces and to leave a projecting tongue having a plurality of rectangular locking-lugs on its opposite sides, and a second rail having a thickened shoulder with a central slot provided

with rectangular recesses of greater dimensions than the locking-lugs in the walls thereof to receive said locking-lugs, and said second rail having inwardly-converging faces 5 adapted to bear on the inwardly-converging faces of the first rail.

4. A rail-joint comprising a rail having a thickened shoulder with its end cut away to leave vertical inwardly-converging faces and 10 to leave a projecting tongue having a plurality of locking-lugs on its opposite sides and having its base cut out to leave a lip, and a second rail having a thickened shoulder with a central slot provided with recesses in the 15 wall thereof to receive said locking-lugs, and said second rail having inwardly-converging faces adapted to bear on the inwardly-converging faces of the first rail, and said second rail having two cut-out portions, the surfaces 20 of which are disposed, respectively, on the base and the lip of the first rail.

5. A rail-joint comprising a rail having a

projecting tongue formed with a plurality of locking-lugs on each side, and a second rail provided with a bifurcated end having recesses therein, each of said recesses being of greater dimensions than the lug disposed therein. 25

6. A rail-joint comprising a rail having a thickened shoulder and having a projecting tongue formed with a plurality of locking-lugs on each side, and a second rail provided with a bifurcated end having recesses therein, each recess being of greater dimensions than the lug disposed therein, and said second rail being provided with shoulders on 30 each side of its bifurcated end. 35

In witness whereof I have hereunto set my hand in the presence of two witnesses.

FLAVIEN ^{his} X BOMBARDIER.
